UNITED STATES PATENT OFFICE

2,506,391

CLAMP TYPE GARMENT HANGER

Hans M. Schliestedt, Chicago, Ill.

Application April 6, 1948, Serial No. 19,380

1 Claim. (Cl. 223—93)

1

My invention relates to garment hangers, an important object of which is to provide a garment hanger with the means for holding a garment, which is draped thereon, securely in place.

A further object of my invention is to provide a garment hanger, having pivotably attached arms, the tips of which are provided with a bearing surface which, when in a downward position, will hold a garment, which is draped over the hanger, securely in place.

A further object of my invention is to provide a sliding hook means, which is pivotably connected to the aforementioned arms at their inner termini in such a way that, when the garment hanger and garment are suspended on a hook, the weight of the said garment hanger and garment will maintain a firm frictional bearing, holding the said garment to the garment hanger.

A still further object of my invention is to provide, in a garment hanger, a knurled or roughened surface on the top side of the bearing plate over which may be draped a light weight garment, such as a woman's slip and having shoulder straps, or like supports.

Other objects and advantages inherent in my invention will become readily apparent from the ensuing description and the accompanying drawings, and in which like parts are designated by like numerals, and in which:

Fig. 1 represents a front view of my invention showing the garment draped thereon in dotted lines and also showing, in dotted lines, an open position of the clamping arms of my garment hanger.

Fig. 2 represents a cross-sectional view taken substantially on lines 2—2 of Fig. 1.

Fig. 3 is a cross-sectional view taken substantially on the lines 3—3 on Fig. 1.

Fig. 4 is a bottom view of a portion of my invention looking in the direction of the arrows 4—4 on Fig. 1.

Referring to the illustrations, my invention is generally designated 5 and consists of a curved hanger of wood or plastic 6, through the center of which a hole 7 is drilled vertically to retain slidably a length of wire 8. The top end of the wire 8 is formed into a hook 9 and its bottom end is flattened at 10 and is provided with a hole 31 through which a pin 11 is fastened.

A pair of flat arcuately curved and tapered arms 12 and 13 are pivotably attached, one on each side of the hanger 6 at 17 by a rivet 18. The outer ends of the arms 12 and 13 are flattened at 14 and held together by a plate 15, the top of

2

which is roughened or knurled at 16. The wider inner ends of the arms 12 and 13 are formed into reverse arcuate bends at 20 and are offset at 19 to afford clearance for the arcuately bent ends 32 of a second similar pair of arcuately curved arms 23 and 24, which in turn are pivotably attached to the hanger 6 at 26 by rivets 27; the outer ends of the arms 23 and 24 being flattened and held together by a plate in a means similar to that of the arms 12 and 13. The curved inner ends 20 of the arms 12 and 13 and the inner curved ends 32 of the arms 23 and 24 are slotted at 21 and 25 respectively.

The ends of the pin 11 attached to the wire 8 project through the said slots 21 and 25 and are peened over at 22 in order to confine the curved inner ends 20 and 32 so that a downward pressure upon the wire 8 will, by means of the pin 11, slots 21 and 25, and the pivoting points 17 and 26, cause the arms 12 and 13, and the arms 23 and 24 to swing pivotably upwardly causing the plates 15 to be free of the top edge of the hanger 6. In this position, the garment 28 may be draped over the hanger 6. Then, when the hanger and garment are suspended from a hook or clothes rack, the weight of the hanger and garment, aided by gravity, will cause the arms 12 and 13, and 23 and 24 to be pulled downwardly until the bottom surfaces 30 of the plates 15 are again bearing upon the surface of the hanger 6 holding the garment 28 firmly therebetween preventing slippage of the said garment 28.

For garments having shoulder straps or like means of support, the top surfaces of the plates 15 are knurled to provide a non-slippable holding surface for the shoulder straps of the said garment 28, as shown in dotted lines in Fig. 1.

It will be noted that this garment hanger requires no spring or adjusting means to maintain a frictional engagement or bearing which hold the garment in place on the hanger, the combined weights of the garment itself and the hanger providing the necessary pressure.

Although I have herein described, rather succinctly, the structural features of my invention, yet it is understood that changes and departures therefrom may be made provided they fall within the purview and definition of the subjoined claim setting forth the limitations thereof.

Having thus disclosed and revealed my invention, what I claim as new, and desire to secure by Letters Patent, is:

A garment hanger of the character described comprising, a curved hanger bar member, a pair

of hanger arms pivotally mounted on each side of the central axis of the said hanger bar member, both pairs of hanger arms being provided with arcuately slotted portions in registered alignment at their inner ends, and provided at their outer ends with interconnecting clamping portions on their top surfaces, and further provided with intermediate arcuate portions, a pivot element fitted into the said arcuately slotted portions, and a hook element having its lower terminus secured to the said pivot element and slidably mounted in the said hanger bar member at

a point intermediate both the said pairs of hanger arms.

HANS M. SCHLIESTEDT.
